UNITED STATES PATENT OFFICE.

FRANK P. BENJAMIN, OF NEW YORK, N. Y.

RAILROAD SIGNALING DEVICE.

SPECIFICATION forming part of Letters Patent No. 399,474, dated March 12, 1889.

Application filed February 11, 1888. Serial No. 263,717. (No model.)

To all whom it may concern:

Be it known that I, FRANK P. BENJAMIN, a citizen of the United States, residing in the city, county, and State of New York, have 5 invented certain new and useful Improvements in Railroad Signaling Devices, of which the following is a specification in such full, clear, concise, and exact terms as will enable any one skilled in the art to which my invention relates to make and use the same, reference being had to the accompanying drawings, making part of this specification, and to the letters and figures of reference marked thereon.

15 My invention consists of certain novel parts and combination of parts constituting an improved system of railroad signaling.

The following is a description of the accompanying drawings and of my invention as embraced and illustrated therein, while the 20 points of novelty will be specifically designated in the concluding claims.

Referring to the accompanying drawings, Figure 1 is a longitudinal section of a railroad-vehicle, taken on the dotted line 1 2, Fig. 2. Fig. 2 is a cross-section of said railroad-vehicle, taken at the dotted line 3 4, Fig. 1. Figs. 3, 4, 5, 6, and 7 are detail views of apparatus which may be employed in the 30 practice of my present invention. Fig. 8 is a top view of a part of a railroad-bed with signaling mechanism connected therewith. Figs. 9 and 10 illustrate, respectively, top and elevation views of a railroad-bed having my 35 present invention applied thereto in two of its many possible modifications; and Figs. 11, 12, 13, and 14, other modifications thereof.

Referring to Fig. 8, along a railroad-bed runs a conductor, W, shown by double lines. 40 At certain points along this conductor W branches (hereinafter designated as the "signaling branches" or "local circuits") are formed by connecting one end of a conductor, S, (shown by a solid black line,) with W at the 45 circuit-closing device M, inside or outside of the rail, leading S along preferably outside the rails some distance, then bringing it between the rails, continuing it some distance farther in the same direction, and joining it 50 to the conductor W again at a point, k. If this local-circuit conductor S is closed, the

current flowing through W, supplied from any suitable source of electricity, will, at its junction with S divide, part flowing through S and part continuing through the conductor W. 55

On each side of a car or engine (see Figs. 1 and 2) are coils C C of insulated wire connected with an electric alarm, A. These coils are hung so that one coil C will pass over all those parts of the local circuits S between 60 the rails on one side of the track, and the other coil C will pass over all those parts of the local circuits between the rails on the other side of the track.

If a vibrating current of electricity of sufficient strength is passing through a local circuit S at the time a coil C passes over it, it will induce a current in the coil C and work the alarm A, as is now well understood in the arts. 65

The following means may be employed to cause part of the current flowing through the wire W to flow through the local circuit S. 70

The box M (see Figs. 3 and 5) contains the following mechanism for making and breaking electrical connection with the line-conductor W and causing part of the current flowing in the line-conductor W to enter the local circuit S. A bar, H, is placed so near the rail, either on the inside or outside thereof, that the wheels of a passing car or engine will run over it and press it down. It rests upon a suitable spring, H', so that it is returned to its original position as soon as the wheels have passed, and it has a projection, 80 H'', on its side placed so that it will engage when it is depressed one arm of a lever, L, and raise the other arm of said lever, which is forked, one part, (the upper,) L', being a plain strip of conducting and paramagnetic 85 material, and the other part, (the lower,) L'', containing a resistance, e, preferably greater than the total resistance of the local circuit S and the mechanism contained therein. When the lever L is not acted upon by the 90 projection H'', it hangs by its weight in the position shown in Fig. 5, and both parts are in electrical contact with the metal strip f. The line-wire W passes through the box M, one end being connected with the lever L 95 and the other end with the strip f. When the lever L is in its normal position, the cur-

rent passing through W will flow through L and f, and the line-circuit will remain unbroken and undivided. The wire of the local circuit S on entering the box M is wound into 5 and forms the coil of the electro-magnet y, which is connected with a short metal strip, g, which is placed close to the path of the lever-arm L', so as to press against the upper fork, L', when and only when L' is raised by the depression of L. Now, when the wheels of a railroad-vehicle pass over the bar H, it will, as shown, raise the lever-arm L' and bring it into electric contact with the strip g, so that a part of the current in W will flow 10 through the coil y into the local circuit S and join the main-line conductor W again at k, Fig. 8, and, although the continuity of the conductor W is not broken, the current flowing therein will pass through the resistance e, and the greater part thus be diverted in said local circuit. Such resistance-piece may be omitted, if desired; but in this device I prefer to employ it. As soon as the current begins to flow in S, the magnet g will attract the upper 15 fork, L', which acts as its armature, and so hold the lever L' up and maintain the connection through the strip g as long as the current continues to flow in local circuit S; but when the current in S is broken the arm L' falls by its own weight, breaks electrical contact with g, and the current in S ceases, and cannot be restored until the electrical contact has been made again between L' and g by the 20 action of a passing wheel, as above described. The strip f, as will of course be understood, is long enough to be in constant electrical contact with arm L'' when the arm L' is held in contact with the armature of the magnet y. This apparatus will be designated hereinafter 25 as the "circuit-closer."

The apparatus, by means of which the current in the local circuit is disrupted may consist of a box, N, (illustrated in detail in Figs. 4 and 6,) in which are two posts, B B', attached 30 to conductor S. A lever, L''', pivoted to post B, rests normally on the post B', forming electrical connection between them. The other arm of this lever extends under a projection on a bar, J, similar in all respects to bar H in Figs. 3 and 5. When a wheel presses J down, it raises L''' off the post B' and interrupts the current in S. As soon as the wheels pass, the bar J rises and the lever L''' falls by its weight to its normal position and restores the 35 connection between the ends of signal-wire S.

Fig. 7 shows another form of circuit making and breaking device which may be employed. By means of this device (illustrated at D, Fig. 8,) if an engine going the direction M' M, Fig. 40 8, sets the signal in the branch S' at M' it will take off such signal by setting the signal in S at M. Referring to Fig. 7, the wire of the local circuit S forms the coils of an electro-magnet, t. The wire of the next local circuit, S', is connected with a pivoted armature, U, pressing against the end of binding-

screw V, with which the other end of S' is connected.

Fig. 8 shows the mechanism above described connected with the roadway. R R is a rail 70 on which the wheels of the train rest. Outside of the rail in the illustration runs the line-wire W, through which a suitable current of electricity provided from any suitable source is continually flowing. The local circuits are shown by the solid line S S. S' S' represent a signaling-wire similar to S S, and shown by the hollowed dotted lines. M M' are circuit-closing devices. N N' are the circuit-breakers on the wire S S and S' S', respectively. D is a circuit-breaking device similar to that shown in Fig. 7, its object being to break any current in S' when a current is flowing through S, and thus provided for breaking the local circuit behind the train 85 when it is running in the direction of M' M. Now, suppose a vehicle to be traveling in the direction of M' M'. When it reaches M, it will cause part of the current in W to flow through S S, and will signal any vehicle provided with 90 coils C and alarm A over that portion of the local circuit-wire S which is between the rails. When it arrives at N, it will break the current in S S and leave it disrupted until another train in its passage again establishes it. 95 During its passage between M and N it will not signal itself, because the signal-wire S between those points is not between the rails, and hence not in inductive proximity to any signaling-coil which it may carry. When 100 said vehicle arrives at M', it will set a current in S' S' and break current therein when it reaches N'. The circuit-making device M' in the second branch is placed very close to the circuit-breaking device N of the first branch, 105 so that a signal is set in the second branch as soon as it is shut off the first branch. If the vehicle move in the direction M' M, it will set the signal behind it in S' at the maker M' and break it by means of D, when it sets the 110 signal in S S at the maker M, as previously described, so carrying a signal, if the branches are continued, always behind it. In Fig. 8 only a fragment of a system is shown, illustrating, as it does, only how a signal may be 115 set always ahead of a train when moving in the direction M' M', and behind it when moving in the direction M' M. Any extension of the systems shown may be employed to secure the desired result.

Fig. 9 shows an engine, E, on the rails R R, going toward the top of the drawings. Systems of local circuits are shown on both sides of the track. On the right side of the engine E the signals are set ahead of the engine, because the system is arranged on that side, so that the engine will run over the circuit-closer M and circuit-breaker N of the local circuit before it arrives at that part of said circuit which is between the rails, and on the 125 left side of the engine the system is arranged in the opposite manner—that is, the engine 130

passes over the part of the local circuit between the rails before it sets a current in said local circuit by passing the circuit closer connected therewith; hence in the system described an engine will always have a signal set ahead on the right and behind on the left side. If the engine E or any other engine in the track receive a signal from the coil on its left side, it will show that the signaling train is ahead, and if it receives a signal from the coil on the right side, it will show that the signaling train is behind.

Fig. 10 shows how the current may be taken from a single wire, W, to supply systems on both sides of the track, a line-wire, W, on poles being led down to the makers M on both sides of the track.

Fig. 11 shows another method of arranging the local circuit closing and breaking devices in connection with the local circuit S. The two local circuit-breakers, N N'', are placed, one at the opposite ends of that part of the local circuit S outside the rails R. Between these local circuit-breakers N N'' the local circuit is divided into two branches, S'' S'''. On S'' close to N is a local circuit-closing device, M'', and on S''' close to N'' is another local circuit-closing device, M'''. These circuit-closing boxes M'' and M''' may be of any suitable construction to be actuated by the passage of the train. The resistance-piece e and the segmental contact-plate f, (illustrated in Fig. 5,) should be omitted, as the resistance K on the line serves in the system shown to divert the necessary current into the local circuit. A train going in the direction N'' N closes the circuit S by closing the branch S''' at M''' and breaks it at N. A train going in the direction N N'' closes S by closing the branch S'' at M'' and breaks it at N''. K is a resistance to divert into the local circuit S when open the requisite quantity of current. The object of this arrangement is that a vehicle going in either direction will cause a signal to be set and maintained in S during the time it is moving between M'' and M'''. Of course the two branches S'' and S''' are normally open. The circuit-breaking devices N N'' are on S, outside the branches S'' and S''', and hence will break a current in either or both. This serves to illustrate one of numerous methods of arranging the circuit breaking and closing devices in the practice of my invention.

Figs. 12 and 13 illustrate how this system of local circuits may be employed to signal trains by means of static induction, according to principles which are now well understood in the art, and an extended reference to which is deemed unnecessary here. The signaling part of the local circuit S, Fig. 12, is brought in inductive proximity to an insulated plate, C', carried in this illustration on the roof of a car and connected by a conductor, P, to a signal, A, and thence to the ground by any well-known means. The vibrations of the electric current in S vary the static charge they induce in C', and so work

the signal A. The signaling part of the local circuit S may be open and branch from the part between M and N, and so receive a static charge whose variations will cause variations of the static charge in C'. In Fig. 13 is shown a section of the car with two insulated plates, one on each side of the roof, connected each with an alarm, A, and each in inductive proximity to a local-circuit wire, S, on each side of the track. The object of the two plates C' is the same as the two coils C C before considered.

Another disposition of the local circuit is illustrated in Fig. 14 of the drawings. In this figure three sets of closed circuits, S, S', and S'', are shown, each circuit being laid first along one side of the track, then along the middle of the track, and along the other side of the track, returning outside the rails to the point of beginning. Now, suppose that portion of said circuits in the middle of the track be in inductive proximity to a device on the train by means of which a vibrating current of electricity is introduced into said circuit when the train is over the same. Said current so introduced in said circuits will work the signal on the right-hand or left-hand side of an approaching train having coils C C in inductive proximity to said lines, depending upon whether the position of said approaching train is behind or ahead of the same. In this system the source of electricity flowing through the local circuits is carried on the train and is introduced into the local circuits by induction, and the advantages incident to the same are, among other things, due to the fact that circuit makers and breakers and other machinery along the line are rendered unnecessary. The use of these constantly closed circuits are not specifically claimed here, but are in a pending application filed February 9, 1889, bearing Serial No. 299,307.

Instead of extending the system of signaling, as illustrated in the drawings, to constantly transmit a warning signal both ahead and behind the train, I may confine the use of my invention to the transmission of a signal in only one direction, and it will of course be understood that my invention is not limited to the precise devices or combinations of devices illustrated and described, as many modifications and adaptations may obviously be employed without departing from either the principle or scope of my invention.

I am aware that it is not new to have a main-line conductor arranged along a railroad-track, including in it a number of make and break devices operated by the passage of the train to cause the current in said line to flow constantly through the train, so that said train will be always in communication with an external telegraphic station, as shown in Letters Patent No. 309,274 to Williams, Barnum, and Ives. I am also aware that it is not new to have a plurality of circuits arranged along a line directly and indirectly in communication with each other, said circuits including the

make and brake devices last above referred to and substantially for the same purpose, said circuits each being constantly in electrical communication with the main line through 5 repeating devices, as shown in Letters Patent No. 343,095 to Williams; but the devices described in the above patents will neither of them accomplish the purposes for which my invention is designed, for, among other things, it is obvious that in neither case is an automatic signal transmitted; and that if it were it would be transmitted to the entire line, and hence its operation would not be confined in either case to any definite area, as mine is 10 to the limits of the local circuit on which the signaling train is located.

It will be observed that the several local circuits employed in my signaling system are so arranged that the impulses flowing through 15 one of them are not communicated to the other circuits, and that the operative electrical impulses caused by the passage of the car are confined within definite limits of operation. This forms one of the cardinal distinctions 20 between a signaling and an ordinary telegraphing device; hence it may properly be said that such circuits are separate and independent.

I claim—

30 1. In a system of railroad-signals in which communication between vehicles is automatically established by means of the inductive effects of a current of electricity, the combination of a plurality of separate and independent local circuits arranged on both sides of the track, a vehicle carrying a plurality of conductors respectively parallel to and in inductive relation to different portions of said local circuits, said local circuits carrying make 35 and break devices in the path of a moving vehicle for the purpose of signaling both ahead and behind it, and an electrical generator the current from which is automatically cut into and out of said local circuits by said make 40 and break devices, substantially as described.

45 2. In a system of railroad signaling in which communication is automatically established between vehicles by means of the inductive effects of a current of electricity, the combination of a vehicle having a plurality of conductors, each including instruments for receiving signals, and a plurality of local circuits arranged on both sides of the track parallel to and in inductive relation to said vehicle-conductors, respectively, substantially as described.

50 3. In a system of railroad-signals in which communication between trains is automatically established by means of the inductive effects of a current of electricity, the combination of a vehicle carrying a conductor with instruments for receiving signals, a local circuit arranged along the line, one part of which is parallel to and in inductive relation to said vehicle-conductor, and another part of which, carrying make and break devices in the path

of a moving vehicle, is out of inductive relation to said vehicle-conductor, and an electrical generator the current from which is cut into and out of said local circuits by said make 55 and break devices, substantially as described.

4. In a system of railroad signaling in which communication is established between vehicles by means of the inductive effects of a current of electricity, the combination of a vehicle carrying a conductor with signaling-instruments, and a plurality of separate and independent local circuits arranged along the line in inductive relation thereto, said local circuits being overlapped, substantially as 60 and for the purpose set forth.

5. In a system of railroad signaling in which communication between vehicles is established by means of the inductive effects of a current of electricity, the combination of a vehicle carrying a conductor with signaling-instruments, and a plurality of separate and independent local circuits arranged along the line in inductive relation thereto having make and break devices in the path of a moving vehicle, said local circuits being overlapped, substantially as described.

6. In a system of railroad-signals in which communication between trains is automatically established by means of the inductive effects of a current of electricity, the combination of a vehicle having a conductor with instruments for receiving signals, a plurality of local circuits arranged along the line, parts of which are parallel to and in inductive relation to said vehicle-conductor and other parts of which, carrying make and break devices, are out of inductive relation to said vehicle-conductor, said local circuits being overlapped, and an electrical generator the current from which is cut into and out of said local circuits by said make and break devices, substantially as described.

7. In a system of railroad signaling in which communication between vehicles is automatically established by means of the inductive effects of a current of electricity, the combination of a vehicle having a plurality of conductors, each including instruments for receiving signals, and a plurality of local circuits overlapped and arranged on both sides of the track in inductive relation to said vehicle-conductors, respectively, substantially as described.

8. In a system of railroad signaling, the combination of a plurality of local circuits, each circuit including make and break devices, and a make-and-break device common to a plurality of said circuits, whereby when the circuit is completed in one of said local circuits it is automatically broken in the other, substantially as described.
